US00D867616S

(12) **United States Design Patent** (10) **Patent No.:** **US D867,616 S**
Malakauskas (45) **Date of Patent:** **** Nov. 19, 2019**

(54) **PREFABRICATED MODULE**

(71) Applicant: **Vastint Hospitality B.V.**, Amsterdam (NL)

(72) Inventor: **Giedrius Malakauskas**, Amsterdam (NL)

(73) Assignee: **Vastint Hospitality B.V.**, Amsterdam (NL)

(**) Term: **15 Years**

(21) Appl. No.: **29/570,383**

(22) Filed: **Jul. 7, 2016**

Related U.S. Application Data

(62) Division of application No. 29/480,005, filed on Jan. 22, 2014, now Pat. No. Des. 765,266.

OTHER PUBLICATIONS

U.S. Appl. No. 15/266,466, filed Sep. 15, 2016, entitled prefabricated Panel for a Building.

(Continued)

Primary Examiner — Brett Miller

(74) *Attorney, Agent, or Firm* — Merchant & Gould P.C.

(57)

CLAIM

The ornamental design for prefabricated module, as shown and described.

DESCRIPTION

FIG. 1 is a top view of a prefabricated module.

FIG. 2 is a door side view of a prefabricated module.

FIG. 3 is a side view of a prefabricated module and panel.

FIG. 4 is a perspective view of an assembled prefabricated module and panels and facade without a ceiling; and,

FIG. 5 is a perspective view showing a complete ground floor of the building and a complete first floor constructed by prefabricated modules and panels and facades.

The broken lines shown in the figures represent environment

and do not form a part of the claimed invention.

1 Claim, 4 Drawing Sheets
